UNITED STATES PATENT OFFICE

CHARLES TEMKOVITS, OF PHILADELPHIA, PENNSYLVANIA

LIQUID COOLING INSTALLATION

Application filed June 16, 1931. Serial No. 544,791.

This invention relates to liquid cooling installations, and has for an object to provide an organization having improved means for controlling the flow of liquids during the cooling process.

The utility of the present invention is more particularly directed to the cooling of milk in dairies, but it is to be understood, that such utility is no limitation upon the invention, and that the device may be employed for cooling liquids of any kind for any purpose, and in any location.

A further object of the invention is to provide in a liquid cooling installation, improved guiding fins and members for preventing the discharge of the liquid longitudinally beyond the ends of the cooling pipes over which it is conducted.

A further object of the invention is to provide a cooling organization employing two different refrigerating mediums with different pipes or coils of pipes for the different types of cooling mediums, and with different types of directing fins upon the different types of pipes.

A further object of the invention is to provide improved means for caring for the expansion and contraction of the cooling pipes incident upon the variations of temperature during, before and subsequent to the refrigeration.

The invention, therefore, comprises an organization which embodies a frame work upon which is mounted a trough or other means for discharging liquid to be cooled, with underlying vertical series of pipes, with centering fins along the bottom of each, the series being divided into two sections, the upper section being normally supplied with cold water, and the lower section with refrigerated gases so that the temperature of the overflowing liquid will be brought gradually from this initial temperature to a very low temperature at the discharge, the water coils or pipes being provided with end fittings having inclined guiding extremities, and with improved types of spoon shaped fins upon the gas section.

The invention is directed to other objects, and possesses other features of novelty and

advantage, some of which, together with the foregoing, will be hereinafter more fully set forth.

In the drawings:

Figure 1 is a view of the entire installation with the housing or enclosing casing removed. 55

Figure 2 is a view of one of the stanchions for supporting the pipe coils, 60

Figure 3 is a fragmentary view partly in elevation and partly in section of the end fittings of the water coils, 65

Figure 4 is a fragmentary view partly in elevation and partly in section of the end fittings of the gas coils, 70

Figure 5 is a view in elevation of one of the guiding fins applied to one of the pipes, as indicated by arrow 5, at Figure 4, and 75

Figure 6 is a view of the spoon shaped fin, taken from the same direction as Figure 5, but removed from the pipe. 70

Like characters of reference indicate corresponding parts throughout the several views. 75

The present installation comprises stanchions 10 and 11 which are supported in any approved manner, as by the frame work 12. As shown at Figure 1, the stanchion is divided into sections vertically, but as shown at Figure 2, the stanchion is unitary. So far as the present invention is concerned, it is immaterial whether such stanchion be integral or in sections. 80

The stanchions are provided at their upper ends with proper facilities, indicated at 13, to receive and support a conduit 14. As noted in the objects of invention, this device is primarily intended for the cooling of milk in dairies, and the fluid cooled, will be herein referred to as milk, but it will be understood that this is only for convenience and no limitation. With this understanding, the conduit 14 will be considered as a conduit or trough for milk with a depending centralizing fin 15. 85

Beneath the conduit 14, the stanchions 10 and 11 will support two separate cooling units; indicated in their entirety as A and B, A being supplied with cold water, the said unit having conduits 16 and 17 for 100

inlet and outlet of such water, which said conduits respectively, pass through openings 18 and 19 in stanchions 11.

This water cooling unit is provided at 5 each end with fittings 20 in the form of return bends, the ends, however, being formed upon planes inclined to a normal vertical as indicated at 21 in Figures 1 and 3. These fittings 20 may be produced in 10 any approved manner, but it is the present intent that they shall be cast integral, and therewith, trunnions 22, which trunnions 22 pass through openings 23 in the stanchion 11 and provide perforations 24, for the receipt of pins 25.

Between the opposed fittings 20, cooling pipes 26 are employed, and as usual, it is the intent that these cooling pipes shall be constructed of relatively thin metal, and 20 the attachment at the end fittings 20 will be made in any approved manner. At the present time, the practice indicates sweating these pipes into the fittings, but it is to be understood, that other means of connection is fully within the scope of the present invention.

Each of the pipes 26 is provided along its longitudinal lower median line with a downwardly extending fin 27. This fin is 30 in accordance with the present day practice in such installations, and serves to centralize the drip of each pipe upon the underlying pipe so that the fluid passing over the several pipes will cover the greatest 35 possible area to fully employ the refrigerating properties of the fluid within the pipe.

The construction of fittings such as that shown at 20, does not seem feasible for the gas section of the cooling coil. A fitting 28 is, therefore, employed for connecting the pipes of the gas section. These pipes correspond in general terms, to the pipes of the water cooling section, and have been given the like number of 26. They are also provided with fins 27 in like manner, and for 45 the same purpose. The end fittings 28 are also provided with the same lugs 22 with the openings 24 to be inserted through the stanchions. The length of these lugs 22 is 50 such that the pipes extending between the stanchions 10 and 11 are free to expand and contract according to the temperature, and such expansion and contraction is compensated for by the sliding action of the lugs 55 22 in the perforations 23 of the stanchions.

The gas pipes 26 may be connected with the fittings 28 also in any approved manner, but preferably, these pipes 26 will be upon the exterior of the fittings as distinguished 60 from being inserted into the fittings as is the case in the water unit, and may be fixed in any approved manner, but the present practice indicates the preference of sweating the pipes upon the fitting.

65 For this type of unit, the pipes are pro-

vided with the fins C. These fins C comprise a strip of metal, either bent or die-cut as occasion may make necessary, having a U-shaped recess 29 properly proportioned to fit the pipes 26 when located at an angle to the horizontal as shown particularly at Figure 4. These fins are dished or spooned as indicated at 30, so that when positioned as shown at Figures 1 and 4, the lower and outer extremity 31 extends well beyond the upper extremity 32 of the underlying fin, providing for properly directing the flowing milk to prevent it escaping over the ends of the pipes 26 onto the fittings.

Underlying the whole, is a trough 33 or receiving conduit of substantially the usual and ordinary type. The gas coil is, of course, provided with inlet and outlet connections 34 and 35. It is designed that the gaseous fluid will be of substantially the usual and ordinary nature, such for instance, as ammonia gas, preferably compressed and liberated.

As such installations in general and their functioning is already so well known in the art, it is believed that a description of the operation of the device would be mere superplusage.

Of course, the liquid cooling installation, herein illustrated, may be modified in various ways without departing from the invention herein set forth and hereinafter claimed.

The invention is hereby claimed as follows:

1. A cooling installation comprising a plurality of pipes arranged in a substantially vertical plane adapted to receive different types of refrigerating fluids, return bends at the ends of certain of the pipes having inclined ends serving as deflecting fins, and other underlying pipes having applied fins serving as deflectors.

2. A cooling installation comprising a plurality of refrigerating pipes all arranged in a vertical organization, return bends for the ends of the pipes having outwardly extending lugs with perforations therethrough, and inclined ends serving as baffles, stanchions at the ends of the bends having perforations receiving the lugs in sliding relation, and pins through the perforations upon the remote sides of the stanchions.

3. A cooling organization comprising a plurality of independent coils, one superposed above the other in the same vertical plane, each of said coils being provided with end fittings having outwardly extending lugs, stanchions located adjacent the ends of the coil and having perforations through which said lugs are inserted, said end fittings constituting return bends formed integral with said lugs and having ends opposite the lugs formed upon inclinations serving as baffles, and other fittings formed with out-

wardly disposed integral lugs, and having pipes connected to their inner ends.

4. A cooling organization comprising separate cooling coils located one above the other in the same vertical plane, some of the pipes of the upper coil being provided with end fittings in the form of return bends, lugs extending outwardly from said fittings, the ends of said fittings opposite the lugs and 10 facing the pipes being formed upon planes angularly disposed to the vertical and serving as directing fins, fittings for the underlying coil provided with outwardly extending lugs, stanchions erected at the ends of 15 said coils and provided with perforations through which all of said lugs are slidably inserted, and spoon shaped fins formed upon the pipes of the underlying coil in vertical alinement.
- 20 5. A fitting for a cooling coil comprising a return bend having its adjacent open ends formed upon planes at an angle to the plane perpendicular to the axes of the openings and substantially parallel with each other.
- 25 6. A fitting for a cooling unit comprising a return bend having the adjacent open ends

formed with beads disposed in planes at an inclination to the plane perpendicular to the axes of said return bend ends so that they are substantially parallel with each other.

7. A cooling unit provided with cooling pipes, and directing fins formed astride the pipes and terminating above the horizontal median line, the greatest dimension of said fins being no more than the diameter of 70 said pipes.

8. A cooling organization comprising a series of pipes arranged in a vertical plane and having a plurality of directing baffles of U-shaped formation set astride, said pipes in vertical alinement, the lower extremity 80 of each being spaced longitudinally beyond the upper margins of the underlying fins, and their transverse dimension being no greater than the diameter of the pipe.

9. As an article of manufacture, a fin for 85 a cooling system comprising a spoon shaped member having a U-shaped recess therein, proportioned to set astride a pipe, and having its inner U-shaped edge proportioned to be fixed to said pipe.
